UNITED STATES PATENT OFFICE.

JAMES MACKEY, OF STEAMBOAT SPRINGS, COLORADO.

WRENCH.

1,009,429.

Specification of Letters Patent. Patented Nov. 21, 1911.

Application filed March 21, 1911. Serial No. 615,974.

To all whom it may concern:

Be it known that I, JAMES MACKEY, a citizen of the United States of America, residing at Steamboat Springs, in the county of 5 Routt and State of Colorado, have invented certain new and useful Improvements in Wrenches, of which the following is a specification.

This invention relates to improvements in 10 wrenches and its object resides in the provision of a wrench of simple construction, the jaws of which are automatically locked in their adjusted position by contact with the nut or other object to which they are 15 applied.

I attain this object by the mechanism illustrated in the accompanying drawings in the various views of which like parts are similarly designated and in which—
20 Figure 1 represents a sectional elevation of the improved wrench with the jaws locked in their relative positions, Fig. 2, a similar view with the parts in the position they occupy when the jaws are unlocked for adjustment and Fig. 3, a transverse section taken along the line 3—3 Fig. 1.

Referring to the drawings by numerals, 2 designates the stationary jaw of the 20 wrench which is formed integral with and at the extremity of a sheath 3 in which the shank 4 of the adjustable jaw 5 is longitudinally movably fitted. The shank 4 has along 25 one of its edges a series of serrations which, when the parts are in the normal, locked position, are engaged by the correspondingly serrated face of a locking member 6 which is laterally movably carried in a recess 7 of the jaw 2. The member 6 has a 30 beveled portion opposite to its serrated face which is normally engaged by the concave edge of a stem 8 which is formed integral with a plate 9, normally supported upon the working face of the jaw 2. The stem 35 8 has a limited, longitudinal movement in a slot 10 formed in the jaw 2 transversely with relation to the recess 7, and its lower extremity protruding beyond the lower end of the said slot, is provided with 40 a milled thumb-piece 12, by means of which it may be readily adjusted for the purpose of unlocking the movable jaw 2. A screw 45 13 which projects through a longitudinal slot in the stem 8 determines the extent of

its longitudinal displacement, and a screw 55 14 which occupies a threaded opening in the wall of the sheath 3, projects into a longitudinal groove 15 in the shank 4 to limit the outward movement of the latter.

When the parts are in the locked position 60 as shown in Fig. 1, the plate 9 is in engagement with the working face of the stationary jaw 2, while its stem 8 holds the locking member 6 in contact with the serrated edge of the shank 4 of the movable jaw 5, 65 by the engagement of its oblique edge with the beveled face of the said member. When it is desired to apply the wrench to a nut or other object, the user separates the plate 9 from the face of the jaw 2 by pressure 70 exerted upon the thumb-piece 12 of the stem 8, which latter, in its adjusted position, is disengaged from the member 6, and permits it to move laterally free from engagement with the serrated edge of the shank 4 75 when the latter is moved longitudinally to separate the two jaws. The two parts are maintained in this position, which is shown in Fig. 2 of the drawings, until, by movement of the jaw 5 against the object to be 80 clamped, the plate 9 is pressed against the face of the jaw 2 when the stem 8 has moved the locking member 6 to its original position in which its serrations interlock with those on the shank 4. The wrench may be 85 removed from the object to which it has been applied by sliding it laterally along the faces engaged by its jaws.

Having thus described my invention what I claim is:

1. A wrench comprising a stationary jaw, a movable jaw having a serrated shank, a laterally movable locking member carried by the said stationary jaw and having serrations to engage those on the shank, and a 90 longitudinally movable element composed of a plate normally engaging the working face of the movable jaw and a stem having an oblique face to engage a face of the locking member opposite to its serrations.

2. A wrench comprising a stationary jaw, a movable jaw having a serrated shank, a laterally movable locking member carried by the said stationary jaw and having serrations to engage those on the shank, and a 95 longitudinally movable element projecting beyond the working face of the movable jaw to engage an object clamped between the two

jaws, the said element being adapted to normally maintain the locking member in engagement with the serrations of the shank.

3. A wrench comprising a stationary jaw, 5 a movable jaw having a serrated shank, a laterally movable locking member carried by the said stationary jaw and having serrations to engage those on the shank, and a longitudinally movable element projecting 10 beyond the working face of the movable jaw to engage an object clamped between the two jaws, the said element having an oblique face which by engagement with the locking member will move it in engagement with 15 the serrations on the shank.

4. A wrench comprising a stationary jaw, a movable jaw having a serrated shank, a laterally movable locking member carried by the said stationary jaw and having serrations to engage those on the shank, and a longitudinally movable element composed 20 of a plate normally engaging the working face of the movable jaw and a stem having an oblique face to engage a face of the locking member opposite to its serrations, and at its extremity, a thumb-piece to facilitate 25 its manipulation.

5. A wrench comprising a stationary jaw having a lateral recess and a relatively 30 transverse slot, a movable jaw having a serrated shank, a locking member movable in said recess and having serrations to engage those on the shank, and an element composed of a stem movable within the said slot and 35 having an oblique face to engage a face on

the said member opposite to its serrations and a plate normally engaging the working face of the movable jaw.

6. A wrench comprising a stationary jaw having a lateral recess and a relatively 40 transverse slot, a movable jaw having a serrated shank, a locking member movable in said recess and having serrations to engage those on the shank, and an element composed of a stem movable within the said slot and 45 having an oblique face to engage a face on the said member opposite to its serrations and a plate normally engaging the working face of the movable jaw, the said stem having at its portion protruding beyond the said 50 slot, a thumb-piece to facilitate manipulation.

7. A wrench comprising a stationary jaw provided with an integral sheath, a movable jaw having a serrated shank within the said sheath, a laterally movable locking member carried on the stationary jaw and having serrations to engage those on the shank, and a longitudinally movable element composed 55 of a plate normally engaging the working face of the movable jaw, and a stem having an oblique face adapted to engage with a face on the said member opposite to its serrations.

In testimony whereof I have affixed my 60 signature in presence of two witnesses.

JAMES MACKEY.
